[57] CLAIM

The ornamental design for a halogen gas leak detector,
as shown and described.

DESCRIPTION

FIG. 1 is a top and left front perspective view of a
halogen gas leak detector showing my new design;

FIG. 2 is a bottom and right rear perspective view
thereof;

FIG. 3 is a top and left front perspective view thereof
with the flexible probe tube in an extended position.

FIG. 1

FIG. 2

FIG. 3
